EGG-SHAPED TOY

Reuben B. Klammer, 245 S. Barrington Ave.,
Los Angeles, Calif. 90049

Continuation-in-part of design application Ser. No.
8,097, Aug. 2, 1967. This application Aug. 15,
1968, Ser. No. 16,075

Term of patent 14 years

Int. Cl. D21—02

U.S. Cl. D34—2

FIG. 1

FIG. 2

FIGURE 1 is a view in perspective showing the egg-shaped toy design of the invention in the character of a lion;

FIGURE 2 is a rear perspective view showing the toy design in the character of a lion;

This is a continuation-in-part application of Ser. No. D. 8,097, filed Aug. 2, 1967.

I claim:

The ornamental design for an egg-shaped toy, substantially as shown and described.
